US00D979608S

(12) **United States Design Patent** (10) **Patent No.:** **US D979,608 S**
Beard et al. (45) **Date of Patent:** **** Feb. 28, 2023**

(54) **INFLATOR**

(71) Applicant: **Signode Industrial Group LLC**,
Tampa, FL (US)

(72) Inventors: **Anthony K. Beard**, Poyen, AR (US);
Joseph W. Gault, Sheridan, AR (US)

(73) Assignee: **Signode Industrial Group LLC**,
Tampa, FL (US)

(**) Term: **15 Years**

(21) Appl. No.: **29/864,193**

(22) Filed: **May 13, 2022**

(57) **CLAIM**

The ornamental design for an inflator, as shown and described.

DESCRIPTION

FIG. 1 is a perspective view of an inflator of our new design. FIG. 2 is a front elevational view of the inflator of FIG. 1. FIG. 3 is a back elevational view of the inflator of FIG. 1. FIG. 4 is a right-side elevational view of the inflator of FIG. 1.

FIG. 5 is a left-side elevational view of the inflator of FIG. 1.

FIG. 6 is a top plan view of the inflator of FIG. 1; and, FIG. 7 is a bottom plan view of the inflator of FIG. 1. The broken lines in the drawings depict portions of the inflator that form no part of the claimed design.

1 Claim, 7 Drawing Sheets
